To all whom it may concern:

Be it known that I, HOWARD S. Fig. 1 is a perspective view; and Fig. 2 is

a top view indicating the different compartments of a combined cigarette box and set of match containers, showing my new design. A dominant feature of my design resides in the harmony of the surface finish between the match containers and the cigarette box.

I claim:

The ornamental design for a combined cigarette box, and set of match containers, substantially as shown and described.

HOWARD S. SCHOLES.
